UNITED STATES PATENT OFFICE.

FREDERICK W. LINAKER, OF DUBOIS, PENNSYLVANIA.

PROTECTIVE SHEATHING FOR SOOT-CLEANER DISTRIBUTING-PIPES.

1,323,880.

Specification of Letters Patent.

Patented Dec. 2, 1919.

Application filed March 30, 1918. Serial No. 225,847.

To all whom it may concern:

Be it known that I, FREDERICK W. LINAKER, a subject of the King of England, residing at Dubois, in the county of Clearfield and State of Pennsylvania, have invented certain new and useful Improvements in Protective Sheathing for Soot-Cleaner Distributing-Pipes, of which the following is a specification.

10 Figure 1 is a view in elevation showing manner of installation of the sheathing on the distributing pipe of a soot cleaner applied to a horizontal or vertical type tube boiler,

15 Fig. 2 is a longitudinal sectional view of one form of the protective sheathing, the sections being broken away, and a portion of the distributing pipe being shown in dotted lines,

20 Fig. 3 is a similar view of another form of the sheathing, showing the sheathing formed of alternate male sections and female sections,

25 Fig. 4 is a similar view showing the sheathing formed of combined male and female sections,

Fig. 5 is a cross sectional view taken on the line V—V of Fig. 3, and

30 Fig. 6 is a perspective view partly broken away of one of the section connector elements of the form shown in Figs. 1 and 2.

In boiler flue cleaners of that type in which the soot is removed from the tubes and other surfaces of the boiler by jets of steam blown from a perforated pipe generally known in the art as a distributing pipe, difficulty has been encountered in protecting the distributing pipe from the intense heat to which same is subjected.

40 It has been proposed, and attempts have been made to provide these distributing pipes with a cast metal sheathing, to prevent the pipe from being burned out, but these attempts heretofore have not been entirely

45 successful, due to the cast iron sheathing having a different coefficient of expansion from that of the distributing pipe or blower element and due further to the fact that under high temperature, it has been found 50 that cast iron not only expands, but enlarges or grows,—that is, it assumes a permanent setting and elongation after expanding. For this reason, after the soot cleaner has been in service for some time, the cast iron 55 sheathing is very much longer than when it was originally installed. This causes a

buckling and bending of the entire blower element, and when different sections were joined together, the strain put upon the joints, due to the growth of the cast iron, 60 was so excessive that the joints would break apart, and the blower element or elements become useless.

In order to overcome this difficulty, I have designed a cast iron sheathing made up in 65 comparatively short sections and which surround the distributing pipe or blower element, the lengths varying according to the tube spacing of different types of boilers. The ends of these sections are made to 70 telescope one within the other, and they are so disposed around and along the distributing pipe or blower element, that there is ample allowance for the growth of the cast iron sheathing without in any way affecting 75 the blower element, since as the cast iron sheathing grows, one piece simply telescopes within another.

Variations of the principle here involved are shown in the accompanying drawing and 80 will be described in detail, it being understood however that changes may be made as may be required for adapting the sheathing to the blower elements with which different types of boilers are equipped, without 85 departing from the spirit of the invention or scope of the same as claimed.

In Fig. 1 the distributing pipe or blower element 10 is inserted through the wall 11 of the furnace in the usual manner, it being 90 understood that the sleeve 12 in the boiler wall through which the blower element is introduced, is considerably larger than the element itself, as the brickwork in expanding, is otherwise liable to cause the element 95 to bind. Of course, provision is made for preventing air leaking into the boiler through this opening, which may be done in any desired or approved manner, different forms of which are known in the 100 trade, and therefore not herein shown.

The sheathing as shown in Fig. 2 of the drawings, consists of a plurality of relatively short sections which are placed around the distributing pipe, in practice, these sections 14 being joined at the end by connectors 15, also of cast iron, and which have an intermediate apertured annular flange 16, the opening in which is of a diameter corresponding to the diameter of the distributing 110 axle, and being recessed at the ends to correspond to the diameter of the sections.

In Fig. 3 the sheathing is formed of cast iron male sections 17 and female sections 18. The latter sections have their ends chambered out, while the male sections have reduced ends 19 that are received within the chambered ends of the female sections.

In Fig. 4 another method of forming the cast iron sheathing is shown in which the sections 20 have an annular enlarged chamber 21 at one end similar to the ends of the sections 18, and at the other end are reduced similar to the sections 17, these sections alternating as shown.

The discharge nipples or nozzles 22, 15 through which the jets of steam are discharged from the distributing pipe 10 extend through the sections of the sheathing and into the distributing pipes. As here shown these nozzles are screwed through 20 both the sectional telescopic cast iron sections of the sheathing and also through the distributing pipe or blower element so as to make a thoroughly substantial and solid construction, and at the same time make a 25 steam-tight joint where the steam is emitted from the element. It will be understood however, that these nozzles may be connected to the blower element in any desired manner. In Fig. 1 the nozzles are shown 30 disposed at an angle as when applied to B. & W. boilers so as to direct the steam jets on diagonal lines between the boiler tubes 23'. In Figs. 3 and 5 these nozzles are 35 shown as extending from the blower element at right angles to the axis thereof, as would be desired in flue cleaners applied to other forms of boilers.

It is understood that these blower elements and sheathing are suitably supported,

the showing in Fig. 1, where the element is applied to a horizontal tube boiler being the employment of a tube bearing and clamps 28. Of course, any desired mounting for the sheathing may be employed without departing from the spirit of the invention here involved.

By this method of construction, provision is made for the expanding of the cast metal sheathing, and its "setting" in its expanded condition, without in any manner affecting 50 the distributing pipe or blower element, preserving the latter in its substantially original condition, and materially increasing the life of the blower element.

What I claim is:—

1. In combination with the blower element of a soot cleaner, a sheathing surrounding said blower element and comprising a plurality of aligned short cylindrical pipe sections, and cylindrical connectors 60 loosely arranged between and receiving therein the adjacent ends of said sections, said connectors each having a central inwardly extending internal annular flange and being of a size to permit longitudinal 65 expansion of the sections therein under temperature changes.

2. The combination with a boiler having water tubes therein and a tubular blower element extending transversely of and above 70 the tubes, of a sectional longitudinally expandable tubular sheathing surrounding said blower element, and tube bearing clamps mounted on one of said water tubes and supporting the sections of said sheathing.

In testimony whereof I affix my signature.

FREDERICK W. LINAKER.
